(57) **CLAIM**

We claim the ornamental design for a utility knife blade storage pack, as shown and described.

DESCRIPTION

FIG. 1 is a top perspective view of a utility knife blade storage pack;

FIG. 2 is left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof; and,

FIG. 8 is a bottom perspective view thereof.

Any portion of the article depicted in broken lines forms no part of the claimed design. Broken lines formed by equal length dashes show unclaimed subject matter.

1 Claim, 5 Drawing Sheets---
